US00D835776S

(12) **United States Design Patent** (10) **Patent No.:** **US D835,776 S**
Veliss et al. (45) **Date of Patent:** **** Dec. 11, 2018**

(54) **CUSHION FOR RESPIRATORY MASK**(71) Applicant: **ResMed Limited**, Bella Vista (AU)(72) Inventors: **Lee James Veliss**, Rotterdam (NL);
Amal Shirley Amarasinghe, Sydney (AU); **Bart Jeremy Caffin**, Sydney (AU); **Joshua Adam Gudiksen**, Sydney (AU); **Eric Siu**, Sydney (AU); **Ian Frederick Johnson**, Sydney (AU); **Richard Sokolov**, Sydney (AU)(73) Assignee: **ResMed Limited**, Bella Vista (AU)(**) Term: **15 Years**(21) Appl. No.: **29/580,520**(22) Filed: **Oct. 11, 2016****Related U.S. Application Data**

(60) Continuation of application No. 29/550,509, filed on Jan. 5, 2016, now Pat. No. Des. 780,304, which is a division of application No. 29/487,923, filed on Apr. 14, 2014, now Pat. No. Des. 757,250, which is a division of application No. 29/458,093, filed on Jun. 17, 2013, now Pat. No. Des. 706,413, which is a division of application No. 29/371,591, filed on May 5, 2011, now Pat. No. Des. 685,463.

CLAIM

The ornamental design for a cushion for respiratory mask, as shown.

DESCRIPTIONFIG. 1 is a front perspective view of a cushion for respiratory mask showing our new design;
FIG. 2 is a front view thereof;
FIG. 3 is a rear view thereof;
FIG. 4 is a top view thereof;
FIG. 5 is a bottom view thereof;
FIG. 6 is a right side view thereof; and,
FIG. 7 is a left side view thereof.

(Continued)

The broken lines in the drawings depict portions of the cushion for respiratory mask that form no part of the claimed design.

1 Claim, 4 Drawing Sheets
